ELECTROMAGNETIC DATA INDICATOR FOR
DATA PROCESSING APPARATUS OR SIMI-
LAR ARTICLE

Raymond J. Milas, Meriden, Conn., assignor, by mesne
assignments, to David S. Hart, Bethlehem, Conn.

Filed Dec. 16, 1963, Ser. No. 77,810

Term of patent 14 years

(Cl. D26—5)

FIG. 1

FIG. 2

FIG. 3

FIG. 4

FIG. 1 is a perspective view of an electromagnetic data indicator for data processing apparatus or similar article embodying the invention;

FIG. 2 is a fragmentary plan view of the same;

FIG. 3 is a fragmentary side view in elevation of the same; and

FIG. 4 is a front view of the same indicator.

The essential features of my new design reside in the portion shown in solid lines. A portion of the drawing is diagonally lined to indicate transparency.

I claim:

The ornamental design for an electromagnetic data indicator for data processing apparatus or similar article, as shown and described.
